(57) CLAIM

The ornamental design for a bottle holder, as shown and described.

DESCRIPTION

A utility patent application entitled, "A Device and Method for Securing an Object," by the same inventor, Ser No. 12/151,107, was filed on May 2, 2008.

FIG. 1 is a perspective view of a bottle holder showing my new design; and,

FIG. 2 is a perspective view thereof.

The broken lines showing a baby bottle illustrates environmental structure and form no part of the claimed design.

1 Claim, 2 Drawing Sheets
